UNITED STATES PATENT OFFICE.

CARL W. TILLMANNS, OF UTICA, NEW YORK.

DESIGN FOR A KNIFE-HANDLE.

46,583.

Specification for Design.

Patented Oct. 20, 1914.

Application filed June 13, 1914. Serial No. 845,032. Term of patent 7 years.

To all whom it may concern:

Be it known that I, CARL W. TILLMANNS, a citizen of the United States, residing at Utica, in the county of Oneida and State of New York, have invented a new, original, and ornamental Design for a Knife-Handle, of which the following is a specification, reference being had to the accompanying drawing, forming part thereof.

Figure 1 is a plan view of one side of a knife handle and Fig. 2 is a plan view of the other side of the knife showing my new design for knife handle.

I claim:

The ornamental design for a knife handle as shown.

CARL W. TILLMANNS.
